TAG PRINTING MACHINE

Carl Williams, Huntington Park, Calif.

Application June 6, 1955, Serial No. 513,411

5 Claims. (Cl. 101—301)

2

Fig. 3 is an oblique sectional view taken on the line 3—3 of Fig. 1, with parts broken away.

Fig. 4 is a view similar to Fig. 1 showing the printing head and the ink-applying means in their printing position with respect to a feed tag.

Fig. 5 is an oblique sectional view taken on the line 5—5 of Fig. 4 with parts removed.

Fig. 6 is a sectional view taken on the line 6—6 of Fig. 4 with parts removed.

10 Fig. 7 is a wiring diagram showing the circuits for interconnecting the components of the device of the present invention to a source of electrical energy.

Referring to the drawings, wherein a preferred form

15 of the invention is shown, the numeral 10 broadly designates a housing preferably fabricated from sheet metal having side members 11, a top and bottom member 12 and 13 respectively, a back member 14 and a front member 15, the front member 15 being hingedly connected to the top member 12 so as to permit the same to be swung

20 upwardly into an open position for permitting inspection and adjustment of the components of the device as will be more fully appreciated hereinafter. The numeral 17 broadly designates a printing mechanism whereas the

25 numeral 19 broadly designates an ink-applying mechanism, the printing mechanism 17 being moved in a printing direction by means of a force-exerting means broadly designated by the numeral 20 and the ink-applying means 19 being moved into ink-applying relationship with respect to the printing mechanism 17 by a force-exerting means broadly designated by

30 numeral 21.

More particularly, the printing mechanism 17 comprises a printing head 22 of any suitable or well-known construction which consists of a plurality of endless

35 ribbons 23 which carry suitable type 24 and which are carried on spaced drums 25, the drums being rotatably carried between spaced side members 26. The side members 26 are interconnected by a top member 27 which is connected by means of a bolt 28 to one end

40 of a lever arm 29. The opposite side members 11 of the housing 10 are reinforced by a pair of upwardly extending standards 30, and a cross-shaft 31 is received in aligned openings 32 formed in each of the standards 30. A disc 33, which has suitably affixed in the center thereof

45 a suitable bearing 34, is rotatably received by shaft 31 and centered thereon by suitable spacers 35. The lever arm 29 adjacent the other end thereof and a reinforcing bar 36 are fixed to disc 33 by means of a suitable U-bolt

50 37 so that the lever arm is rockably supported about the axis of shaft 31 for moving the printing head 22 up and down from an "at rest" position, Fig. 1, to a printing position, Fig. 4. The lever arm is urged to move

55 so as to position the printing head in its "at rest" position by means of a suitable tension spring 38 which is anchored at one end to a suitable eye bolt 39 carried by the top member 12 and at its opposite end to an eye bolt 40 secured to lever arm 29, and suitable counterweights 41 are carried adjacent the end of lever arm 29

60 so as to aid the tension spring in urging the lever arm to move or rock the printing head into its raised or "at rest" position. The maximum inclined position of the lever arm is defined by an abutment bar 42 which is L-shaped in configuration and one end of which is secured by means of a suitable screw 43 to the top

65 member 12 of the housing 10 and the other end of which has suitably clamped thereto a suitable buffer pad 44, preferably formed of rubber or like material, by opposed clamp members 45 urged together in clamping

70 relationship by means of a cross bolt 46. It will be appreciated, therefore, that the tension spring 38 and the counterweights 41 cause or urge the lever arm to swing the printing head into its raised or "at rest"

75

A further object of the present invention is to provide a device of this type with a printing head and ink-applying means and means for automatically moving the printing head into printing relationship with respect to a feed tag and the ink-applying means to a position out of the path of travel of the printing head.

A further object of the present invention is to provide a device of this type with a printing head and ink-applying means and electrically responsive means for moving the printing head in a printing direction and the ink-applying means into ink-applying relationship with respect to said printing head.

Further objects and advantages of the present invention will be apparent to those skilled in the art upon perusal of the following description and claims and the accompanying drawings in which:

Fig. 1 is a longitudinal, vertical sectional view of a device embodying the principles of the present invention, showing the printing head and the ink-applying means in their "at rest" or non-printing positions.

Fig. 2 is a vertical sectional view taken on the line 2—2 of Fig. 1 with parts broken away.

position and that the maximum inclined position of the lever arm relative to the horizontal is defined by the lever arm striking or being urged against the buffer pad 44 of the abutment rod 42.

The ink-applying mechanism 19 consists of an ink pad 47 of any suitable or well-known construction which is hingedly connected as at 48 to a cross bar 49 of a housing reinforcing member 50. The ink pad 47 is also link-connected for up and down swinging movement by means of a suitable link 51 to a lever arm 52 which in turn is swingably connected for up and down swinging movement by means of a pin 53, pin 53 being supported between opposite reinforcing members 54 of the housing 10. When the printing head 22 is in its raised or "at rest" position, the lever arm 52 upon being rocked to its maximum forwardly inclined position, swings the ink pad 47 upwardly a distance sufficient to move the same in ink-applying relationship with respect to the downwardly positioned type 24 of the typing ribbons 23. When the printing head 22 is carried downwardly into the printing relationship to a print-receiving card 55 by the lever arm 29, the ink pad 47 is caused to swing downwardly out of the path of travel of the printing head, and upon the printing head 22 resuming its raised or "at rest" position the ink pad 47 is again caused to swing upwardly into ink-applying relationship with respect to said printing head 22.

As previously suggested, the force-exerting means 19 are effective for causing the lever arm 29 to swing downwardly in a printing direction whereas the force-exerting means 21 are effective for causing the ink pad 47 to swing upwardly in ink-applying relationship with respect to the printing head 22 after the printing head has again resumed its raised or "at rest" position.

The force-applying means 19 consists preferably of a solenoid 55a of any suitable or well-known construction which has a core 56 and a push rod 57 secured to one end of said core. The push rod 57 has affixed to the end thereof by means of a suitable bolt 58 a cushioning pad 59 preferably formed of rubber or similar type material, and the solenoid is so positioned that the force exerted by the push rod 57, upon the solenoid being energized, against the lever arm 29 is sufficient to rock the same downwardly in a printing direction and consequently move the printing head 22 into contact with the card 55. When solenoid 55a is de-energized the force exerted by the tension spring 38 and the counter-weight 41 is sufficient to rock the lever arm 29 upwardly into its "at rest" position against the buffer pad 44.

The force-exerting means 21 is also preferably in the form of a solenoid 60 which has a core 61 which is link connected by a link 62 to the lever 52. When lever arm 52 is in its downwardly inclined position so as to position the ink pad 47 in its downwardly extending position out of the path of travel of the printing head 22, the solenoid 60 upon being energized causes the lever arm 52 to swing upwardly and the ink pad 47 to swing in its ink-applying position relative to the printing head 22. A normally open microswitch 63 is positioned in the housing and has a contact arm 64 which is positioned in the path of travel of lever 29, and a suitable "on-off" switch 65 is carried by the top member 12 of the housing 10.

The solenoid 55a is secured by means of bolts 66 to a bracket 67 of reinforcing member 50 while solenoid 60 is secured by bolts 68 to a reinforcing member 69 of housing 10. The microswitch 63 is likewise suitably anchored to member 50 so as to position the same in the path of travel of lever 29 as previously suggested.

Referring now particularly to Fig. 7 of the drawings, one terminal 70 of the "on-off" switch 65 is connected to a suitable source of electricity by means of a lead 71 and the other terminal 72 is connected to one terminal 73 of activator switch 74 by means of a lead 75.

Another terminal 76 of the switch 74 is connected by a lead 77 to one terminal of solenoid 60 and the other terminal of solenoid 60 is connected to a terminal 78 of microswitch 63 by a lead 79. Another terminal 80 of the microswitch 63 is connected by means of a lead 81 to the source of electrical energy so that when the "on-off" switch 65 is closed and the normally open microswitch 63 is closed by reason of the printing lever being in its upwardly inclined position, the solenoid 60 will be energized so as to urge the lever 52 upwardly a distance sufficient to move the ink pad 47 in ink-applying relationship with respect to the printing head 22. The switch 74 has a contact arm 82 which is normally urged in contact with terminal 76; however, when a switch button 83 is forced inwardly, either by the feed bag or by mechanism associated with the feed bag sewing machine or in any other manner, the contact arm 82 is forced to swing into contact with a terminal 84 which in turn is connected by a lead 85 to one terminal of the solenoid 55a. The other terminal of solenoid 55a is connected to the source of electrical energy by lead 81 so that upon the switch 74 being activated solenoid 55a will be energized.

In operation, after the "on-off" switch 65 is closed the solenoid 60 is immediately energized and the ink pad 47 consequently urged in ink-applying relationship with respect to the printing head 22. When the contact arm 82 is moved into contact with terminal 84 of switch 74, the solenoid 55a is energized and the push rod 57 exerts a force against lever 29 sufficient to overcome the force of the tension spring 38 and the counter-weights 41, the printing head consequently moving into printing relationship with card 55 and swinging the ink pad 47 out of its path of travel into the position shown in Fig. 4. It will be appreciated that the printing head 22 will be held against the card 55 as long as the solenoid 55a is energized. When the contact arm 82 is allowed to resume its normal position against terminal 76 the force exerted by the tension spring 38 plus the counter-weights 41 urges the lever 29 to swing upwardly into its forwardly inclined position against the abutment bar 42. It will be appreciated that the contact arm 64 of normally open microswitch 63 breaks the circuit to solenoid 60 when the lever 29 is moved from its "at rest" position. Therefore, when the contact arm 82 resumes its normal position against terminal 76 solenoid 55a is not energized until the lever 29 is rocked upwardly by the force exerted by spring 38 and counter-weight 41 a distance sufficient to move arm 64 of microswitch 63 a distance sufficient to close the circuit. Immediately upon the circuit being closed the solenoid 60 is energized and the lever 52 moved upwardly a distance sufficient to swing the ink pad 47 into ink-applying relationship with respect to the printing head 22. It will be appreciated, therefore, that the contact arm 82 of switch 74 breaks the circuit of solenoid 60 and applies circuit to solenoid 55a at the same time. When contact arm 82 of switch 74 resumes its normal position, solenoid 60 is energized only when lever 29 is moved upwardly against contact arm 64 of microswitch 63 a distance sufficient to close this circuit.

A suitable open-end tray 86 is provided for carrying a plurality of cards 55 and it will be appreciated that the tray is so positioned that the operator can easily fill the tray with cards or remove therefrom the uppermost coded card. The tray is preferably supported in a forwardly inclined position by means of a front supporting member 87 and a rear pad 88, the pad 88 being preferably formed of rubber or similar material so as to absorb the shock of the printing head 22. The tray is also centered with respect to the printing head 22 by means of a guide member 89 and it will be appreciated that the tray can be so constructed as to be adjustable for accommodating therein cards of various sizes and shapes.

An ink tube 90 is also provided which leads from the

top member 12 to the ink pad 47 when the pad is in ink-applying relationship with respect to the printing head 22 for permitting the same to be soaked with a quantity of ink.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

What is claimed is:

1. A stamping machine comprising a printing head, a lever arm fixed to said printing head and swingably connected for up and down swinging movement about a rearwardly disposed transverse axis for moving said printing head from an at-rest position to a printing position, a swingably mounted ink pad urged to swing by said printing head from an ink applying position relative to said printing head to a position out of the path of travel of said printing head upon movement of said printing head toward its printing position, a lever arm supported for swinging movement about an axis substantially parallel with the first mentioned axis, a link interconnecting the second lever with said ink pad for effecting swinging movement of said ink pad in its ink applying direction in response to swinging movement of said second lever in one direction, electrically responsive force exerting means for urging the first lever to move said printing head in a printing direction when energized, electrically responsive force exerting means for urging the second lever to swing in said one direction for moving said ink pad in an ink applying direction when energized, a source of electrical energy, an actuating switch having normally open contacts for connecting the first force exerting means with said source of electrical energy and normally closed contacts for connecting the second force exerting means to said source of electrical energy, and a normally open control switch in the path of travel of the first lever and positioned to be actuated by contact with said first lever for effecting energization of the second force exerting means for initiating movement of said ink pad into its ink applying position when said printing head assumes its at-rest position.

2. A stamping machine comprising a printing head, a lever arm fixed to said printing head and swingably connected for up and down swinging movement about a rearwardly disposed transverse axis for moving said printing head from an at-rest position to a printing position, resilient means connected with said lever for urging said printing head to assume its at-rest position, a swingably mounted ink pad urged to swing by said printing head from an ink applying position relative to said printing head to a position out of the path of travel of said printing head upon said printing head moving toward its printing position, a lever arm supported for swinging movement about an axis substantially parallel with the first mentioned axis, a link interconnecting the second lever with said ink pad for effecting swinging movement of said ink pad in its ink applying direction in response to swinging movement of said second lever in one direction, electrically responsive force exerting means for urging the first lever to move said printing head in a printing direction when energized, electrically responsive force exerting means for urging the second lever to swing in said one direction for moving said ink pad in an ink applying direction when energized, a source of electrical energy, an actuating switch having normally open contacts for connecting the first force exerting means with said source of electrical energy and normally closed contacts for connecting the second force exerting means to said source of electrical energy, and a normally open control switch in the path of travel of the first lever and positioned to be actuated by contact with

5 said first lever for effecting energization of the second force exerting means for initiating movement of said ink pad into its ink applying position when said printing head assumes its at-rest position.

3. A stamping machine comprising a printing head, a lever arm connected to said printing head and swingable about a rearwardly disposed transverse axis for moving said printing head from an at-rest position to a printing position, an ink pad swingably carried to move from an ink applying position to a position out of the path of travel of said printing head, a second lever arm swingable about a rearwardly disposed axis substantially parallel to the first mentioned axis, a link interconnecting the second lever with said ink pad for moving said ink pad into its ink applying position relative to said printing head upon movement of said second lever in one direction, a solenoid for urging the first lever to move said printing head in a printing direction when energized, a solenoid for urging said second lever in said one direction when energized, an actuating switch having normally open contacts for connecting the first mentioned solenoid to a source of electrical energy and normally closed contacts for connecting the second mentioned solenoid to said source of electrical energy, and a normally open switch in the circuit of the second mentioned solenoid and positioned in the path of travel of said first lever and closed by contact with said first lever when said printing head assumes its at-rest position for energizing the second mentioned solenoid for initiating movement of said ink pad into its ink applying position relative to said printing head.

4. A stamping machine comprising a printing head, a lever arm connected to said printing head and swingable about a rearwardly disposed transverse axis for moving said printing head from an at-rest position to a printing position, a swingably mounted ink pad urged by said printing head to swing from an ink applying position to a position out of the path of travel of said printing head upon movement of said printing head toward its printing position, a second lever arm swingable about a rearwardly disposed axis substantially parallel to the first mentioned axis, a link interconnecting the second lever with said ink pad for moving said ink pad into its ink applying position relative to said printing head upon movement of said second lever in one direction, a solenoid for urging the first lever to move said printing head in a printing direction when energized, a solenoid for urging said second lever in said one direction when energized, an actuating switch having normally open contacts for connecting the first mentioned solenoid to a source of electrical energy and normally closed contacts for connecting the second mentioned solenoid to said source of electrical energy, and a normally open switch in the circuit of the second mentioned solenoid and positioned in the path of travel of said first lever and closed by contact with said first lever when said printing head assumes its at-rest position for energizing the second mentioned solenoid for initiating movement of said ink pad into its ink applying position relative to said printing head.

5. A stamping machine comprising a printing head, a lever arm connected to said printing head and swingable about a rearwardly disposed transverse axis for moving said printing head from an at-rest position to a printing position, resilient means connected with said lever arm for urging said printing head to assume its at-rest position, a swingably mounted ink pad urged by said printing head to swing from an ink applying position to a position out of the path of travel of said printing head upon movement of said printing head toward its printing position, a second lever arm swingable about a rearwardly disposed axis substantially parallel to the first mentioned axis, a link interconnecting the second lever with said ink pad for moving said ink pad into its ink applying position relative to said printing head upon movement of said second lever in one direction, a solenoid for urging the first lever to move said printing head in a printing direction when energized, a solenoid for urging said second lever in said one direction when energized, an actuating switch having normally open contacts for connecting the first mentioned solenoid to a source of electrical energy and normally closed contacts for connecting the second mentioned solenoid to said source of electrical energy, and a normally open switch in the circuit of the second mentioned solenoid and positioned in the path of travel of said first lever and closed by contact with said first lever when said printing head assumes its at-rest position for energizing the second mentioned solenoid for initiating movement of said ink pad into its ink applying position relative to said printing head.

first lever to move said printing head in a printing direction when energized, a solenoid for urging said second lever in said one direction when energized, an actuating switch having normally open contacts for connecting the first mentioned solenoid to a source of electrical energy and normally closed contacts for connecting the second mentioned solenoid to said source of electrical energy, and a normally open switch in the circuit of the second mentioned solenoid and positioned in the path of travel of said first lever and closed by contact with said first lever when said printing head assumes its at-rest position

5

for energizing the second mentioned solenoid for initiating movement of said ink pad into its ink applying position relative to said printing head.
